DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

HEATING-SURFACE-CLEANING DEVICE

Application filed September 26, 1923. Serial No. 664,944.

My present invention relates to devices for cleaning the heating surfaces of steam boilers, boiler economizers, air heaters and the like, and will be best understood from the following description and the annexed drawings, in which Fig. 1 is a vertical section of a boiler economizer to which my invention has been applied; Fig. 2 is an enlarged section through one of the nozzles of an element; Fig. 3 is a side elevation of the economizer shown in Fig. 1, with some of the parts broken away; Fig. 4 is an enlarged side view of an element control head, such as is shown in Figs. 1 and 3, some of the parts being broken away in Fig. 4; Fig. 5 is a front elevation of Fig. 4, and Fig. 6 is an enlarged longitudinal section of the inner end of one of the element supports shown in Fig. 1.

Like reference characters indicate like parts in the several views.

In the illustrative embodiment, the walls 10, 11, 12 and 13 define a flue through which waste gases from a boiler may be passed, the plate 14 separating this flue into two passages, the passage at the right of the plate 14 in Fig. 1, in the illustrative embodiment, carrying the gases upward, such gases then passing over the top of the plate 14 and downward over the tubes 15 of the economizer, these tubes extending between banks of headers 16 on either side of the flue in a well-known manner, so that the water passing through the economizer will flow back and forth across the flue and, at the same time, longitudinally thereof, the water inlet, in the illustrative embodiment, being indicated at 17, and the water outlet at 18, the water thus flowing in a generally upward direction in the form shown while the gases flow in a generally downward direction over the tubes 15.

As is well known, heating surfaces exposed to heating gases become coated with soot and other deposits which prevent the transfer of heat from the gases to the heating surfaces, and it is advantageous, therefore, to clean such deposits from these surfaces from time to time. This is ordinarily accomplished by so-called "soot blowers" by which jets of fluid, usually steam, are di-

rected against the surfaces to be cleaned. Under certain conditions, however, such jets of steam may not be sufficient to thoroughly cleanse the heating surfaces, and washing with water or other cleaning fluid may then be resorted to. In the arrangement which I have illustrated, provision is made by which more than one kind of cleaning fluid may be supplied to the cleaning elements at the will of the operator, so that, for instance, steam may be used from time to time to clean the heating surfaces from soot and when the deposits become of such a character, in spite of this blowing with steam, as to make washing with water or other cleaning fluid desirable, then the operator may direct such washing fluid to the heating surfaces through the same elements as are used for applying the steam.

As soot blowers have been heretofore arranged, when extending across a row of tubes to be cleaned, a plurality of openings or nozzles has been provided in the element in sufficient number to clean all of the surfaces simultaneously, the blower element being made rotatable so as to increase the area cleansable in a plane at right-angles to the axis of rotation of the blower element. This involves not only providing a very large number of nozzles, but also involves the use of a considerable quantity of steam at any given instant during the cleaning operation. Furthermore, where the boiler or other apparatus to be cleaned is very wide, the number of nozzles taking steam from the element becomes so large that the steam is unevenly distributed across the boiler, and to avoid this, it has been necessary to provide a separate element extending in from each side of the boiler, half way across the boiler. In the arrangement illustrated, I have shown an element which avoids all of these difficulties.

In the illustrative arrangement, a plurality of blower elements 19 are shown extending across the flue between the walls 10 and 11, these elements being located, as shown best in Fig. 3, so that all of the surfaces to be cleaned may be reached. Since they are all alike, however, a description of one of

them will be sufficient. The element 19 is provided with a plurality of openings through which the fluid may be discharged and preferably these openings are formed as best shown in Fig. 2, as a nozzle 20 screwed or otherwise fastened into the wall of the tube 19 and having its outer end substantially at the surface of the blower 19. The opening 21 in this nozzle is preferably formed with a cylindrically shaped opening, as illustrated in Fig. 2, when the element 19 is used for the discharge of both steam and cleaning liquid. It will be understood, however, that the shape of the opening 21 may be varied in accordance with the desired results. By making the exterior of the nozzle flush with the exterior of the tube 19, the tube 19 may be passed through intermediate supports between the walls 10 and 11, such as the plate 14, and through any other similar plates, which may exist in the apparatus to be cleaned and may be drawn longitudinally through openings in such supporting plates, if desired.

In the illustrative embodiment, one end of the element 19 extends into a tubular support 22 which, in turn, is slidingly supported by the wall 11 as by a bracket 23. The inner end of the tubular support 22 is formed with an opening through which the element 19 extends, as shown best in Fig. 6, the support 22 being fastened to the element 19 by welding or in any other suitable manner.

A sleeve 24 is slidingly mounted in the support 22 and extends over the end of the blower tube 19, as shown in Figs. 4 and 6. The outer end of sleeve 24 is connected to a stationary fluid supply pipe 25 in a well-known way, so as to permit the sleeve 24 to rotate while maintaining a tight joint. In the illustrative embodiment, a T 26 connects pipe 25 with pipes 27 and 28, having hand valves 29 and 30, respectively, the pipe 27 connecting to a vertical pipe 31 leading to a pipe 33 connected to a source of fluid supply, as water, for instance, and the pipe 28 connecting to a vertical pipe 32 leading to a pipe 34 connected to another source of fluid supply, as steam, for instance.

On the sleeve 24, in the illustrative embodiment, is a chain sheave 35 operated by a chain 36 extending down to a convenient distance from the floor. Also connected to the sleeve 24 is a cylindrical member 37 which extends over a projection 38 on the end of the support 22. The member 37 has a plurality of angularly-disposed slots 38' through which project the pin ends 39 of screws 40 threaded in holes in the projection 38. These pin ends 39 are also utilized as fastening means to connect a sheave 41 to the support 22, such sheave being free from the member 37. Sheave 41 is operated by a chain 42. A spring 43 between a shoulder on sleeve 24 and the end of support 22 serves to keep the pin ends

39 against one side of each of the slots 38'. This side of the slot 38' may be supplied with a plurality of equally spaced recesses 44 for a purpose to be described more in detail hereinafter.

In the illustrative arrangement, it will be noted that the tubes 15 are equally spaced in each row and that the openings 21 are spaced apart a distance equal to the distance between three tubes 15. In other words, only one-third the usual number of openings are provided.

To clean a set of the tubes in the illustrative embodiment, one of the hand valves 29, 30 will be opened to connect the pipe 25 and sleeve 24 with the desired source of fluid supply. Such fluid will flow into the end of the blower element 19 and out of the openings 21 and the element 19 will be rotated back and forth by the chain 36, the rotation of sleeve 24 being transmitted to support 22, to which pipe 19 is connected, by the engagement of the pins 39 with the corresponding recesses 44 in the slots 38'. After the tubes against which the openings 21 are directed are cleaned, chain 42 is pulled while chain 36 is held stationary. This produces a relative rotary motion between member 37 and pins 39 and moves the latter out of the recesses 44 with which they have been engaged, and along the angular slot 38', thus moving the pins longitudinally of the axis of the element and with them the support 22 and the pipe 19 to which it is connected. This will be continued until the next recesses 44 are entered by the pins 39, when the operator will know that the openings 21 have been shifted to bring them opposite the next set of tubes 15, when the operation of cleaning by rotating the sheave 35 is repeated, the chain 42 at this time being freed, so that relative rotation between sheaves 35 and 41 does not occur during this cleaning operation. This step-by-step shifting of the openings 21 will be repeated until all of the tubes 15 have been cleaned.

The above arrangement provides a yielding connection between the operating element exemplified by the sheave 35 and the pipe 19. It will be noted that the connection comprises two members, one formed by the sleeve 37 and the other by one or more pins 39, which are held in yielding engagement at the recess or recesses 44, by means of the spring 43. When this yielding connection is released by holding the sheave 35 stationary, then the rotative movement of the sheave 41, which has been transmitted to the pipe 19, is changed to a lengthwise movement of the pipe.

In the specific illustration, each slot 38' will have a recess 44 at each end and one in the middle because there are three times as many tubes 15 across the economizer as there are openings 21. This number will be varied, obviously, in accordance with the relation between the tubes 15 and openings 21.

To provide for any leakage of fluid past the joint between the sleeve 24 and pipe 19, an opening 45 may be provided in support 22 to permit such fluid to escape.

It will be understood that the embodiment of my invention may be widely varied and that certain portions of it may be used without other portions.

While I have shown my invention applied to the cleaning of water tubes, it will obviously be applicable to the cleaning of any heating surfaces, particularly when such surfaces are formed as spaced tubes, or ducts, as in air heaters, and the like.

I claim:

1. In a device for cleaning the surfaces of uniformly spaced tubes exposed to gases, a rotatably mounted tubular element extending across the tubes and having openings to direct jets of cleaning fluid against such tubes, the distance between said openings along said element being a multiple of the distance between two adjacent tubes, means to rotate said element, a member rotatable with said element and arranged to be rotated relatively thereto, means to rotate said member relatively to said element and connections between said element and said member to move said element lengthwise by such relative rotation.

2. In a device for cleaning the surfaces of uniformly spaced tubes exposed to gases, a rotatably mounted tubular element extending across the tubes and having openings to direct jets of cleaning fluid against such tubes, the distance between said openings along said element being a multiple of the distance between two adjacent tubes, means to rotate said element, a member rotatable with said element and arranged to be rotated relatively thereto, means to rotate said member relatively to said element, connections between said element and said member to move said element lengthwise by such relative rotation, and means whereby said element may be retained against longitudinal movement after it has moved a distance equal to the distance between two adjacent tubes.

3. In a heating surface cleaning device, a pipe having means to project cleaning fluid on to said surface, means supporting said pipe and permitting its being rotated and moved lengthwise, an operating element, and a yielding connection between said element and pipe and adapted upon operation of said element to cause rotation of said pipe or to yield and cause lengthwise movement thereof.

4. In a heating surface cleaning device, a pipe having means to project cleaning fluid on to said surface, means supporting said pipe and permitting its being rotated and moved lengthwise, an operating element, a connection between said element and pipe and including two members, one secured to said pipe and one to said element, and means

resiliently holding said members against relative movement.

5. In a heating surface cleaning device, a pipe having means to project cleaning fluid on to said surface, means supporting said pipe and permitting its being rotated and moved lengthwise, an operating element, a connection between said element and pipe and including two members, one secured to said pipe and one to said element, means resiliently holding said members against relative movement, and means to release said holding means.

6. In a heating surface cleaning device, a pipe having means to project cleaning fluid on to said surface, means supporting said pipe and permitting its being rotated and moved lengthwise, an operating element, a connection between said element and pipe and including two members, one secured to said pipe and one to said element, means yieldingly holding said members in engagement with each other, rotative operation of said element being transmitted through said members to said pipe, and means to change said rotative movement into lengthwise movement of said pipe.

7. In a heating surface cleaning device, a pipe having means to project cleaning fluid on to said surface, means supporting said pipe and permitting its being rotated and moved lengthwise, a rotatably mounted operating element and a connection between said element and said pipe comprising an inclined slot and pin, and a recess in a side of said slot in which said pin is received, whereby rotative movement of said element is imparted to said pipe.

8. In a heating surface cleaning device, a pipe having means to project cleaning fluid on to said surface, means supporting said pipe and permitting its being rotated and moved lengthwise, a rotatably mounted operating element and a connection between said element and said pipe comprising an inclined slot and pin, a recess in a side of said slot in which said pin is received, whereby rotative movement of said element is imparted to said pipe, and means to release said pin from said recess, whereby continued rotation of said element will cause lengthwise movement of said pipe.

9. In a heating surface cleaning device, a pipe having means to project cleaning fluid on to said surface, means supporting said pipe and permitting its being rotated and moved lengthwise, a rotatably mounted element, a member secured to said element, a second member secured to said pipe, one of said members having an inclined slot and the other having a pin engaged in said slot, said slot having a recess in one side thereof into which the pin may be received, whereby rotative movement of said element is transmitted to said pipe, and means for holding one

of said members stationary with respect to the other, whereby said pin is released from said recess and moved along said slot to cause lengthwise movement of said pipe.

- 5 10. In a heating surface cleaning device, a pipe having means to project cleaning fluid on to said surface, means supporting said pipe and permitting its being rotated and moved lengthwise, two sleeves rotatably
10 mounted concentrically with respect to each other, and to said pipe, and operative connections between each of said sleeves and said pipe, one of said connections being adapted to cause rotation of said pipe upon rotation
15 of one of said sleeves and the other of said connections being adapted to cause lengthwise movement of the pipe upon rotation of one sleeve with respect to the other.
11. In a heating surface cleaning device,
20 a pipe having means to project cleaning fluid on to said surface, means supporting said pipe and permitting its being rotated and moved lengthwise, a rotatable operating element, means to change rotating movement of said element into rotation of said pipe, and means to change rotating movement of said element into longitudinal movement of the pipe.
